UNITED STATES PATENT OFFICE.

JAMES W. PARKER, OF PALMYRA, WISCONSIN.

IMPROVEMENT IN IMPLEMENTS FOR HARVESTING CORN.

Specification forming part of Letters Patent No. **154,765**, dated September 8, 1874; application filed August 24, 1874.

To all whom it may concern:

Be it known that I, JAMES W. PARKER, of Palmyra, Jefferson county, Wisconsin, have invented a Corn-Cutter, of which the following is a specification:

My corn-cutting device is constructed to operate and use upon the leg and foot of the operator instead of by hand, as is the more frequent mode of using corn-cutting devices or implements.

Figure 1 is a side perspective view of the device. Fig. 2 is an end view of the same.

The device is constructed by attaching a knife, A, some nine inches long, and of proper width and shape, by the shank end, with the edge downward, in a transverse position, to a stirrup or standard, B, fitted properly to the leg and foot of the operator, and strapped or fastened thereon, so as to cause the blade to extend in a right angle or horizontal position from the leg, and outward at about the ankle-joint, and at a proper forward angle of cut of about forty-five degrees from a vertical line, so as to enable the operator to strike the corn-stalks with an advancing and downward motion of the knife, and thus perform the cutting

wholly with the leg and foot thus armed, and leaving the hands and arms free to gather and handle the detached stalks. The stirrup is so curved at the bottom end *c c* as to clasp the sole of the foot, and at the top end *c*, as also to partially embrace the leg. Both of said embracing ends are constructed with loops *d* to receive the fastening-straps. The stirrup or standard, at about the region of the ankle-joint, also has a joint, *e*, to admit of a more free and easy action in use.

Having thus described my invention, what I desire to claim, and secure by Letters Patent, is—

The within-described corn-cutting device, consisting of a cutting-blade, attached at the shank end to a standard, provided with means of securing the same to the leg and foot of the operator, both above and below the ankle-joint, substantially as shown, and for the purposes described.

JAMES W. PARKER.
